(57) **CLAIM**

The ornamental design for an air cooler, as shown and described.

DESCRIPTION

FIG. 1 is a perspective view of an air cooler, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof; and,

FIG. 8 is an enlarged bottom plan view thereof.

The broken lines shown in the figures are for the purpose of illustrating portions of the air cooler and form no part of the claimed design.
